APPARATUS FOR USE IN WINDING
THREADS AND THE LIKEMoulton L. Hudson, Enka, N. C., assignor to
American Enka Corporation, Enka, N. C., a corporation of Delaware

Application December 8, 1942, Serial No. 468,273

10 Claims. (Cl. 242—18)

The present invention relates to an apparatus for winding threads and the like and more particularly to a simplified thread guide mounting for use on a reciprocating traverse member.

In collecting threads such as rayon on rotating collecting devices, for example, driven bobbins, spools, etc., it is necessary to guide the thread back and forth across the face of the collector in order to build up a package of controlled configuration. The guiding of the threads is usually accomplished by means of a traverse member which carries thereon a number of thread guides, corresponding to the number of collectors, and which reciprocates axially of the latter. Thread guides, in the past, have been mounted on the traverse members by means of nut and bolt assemblies including locking washers, collars, etc.; and if they are mounted for movement in a direction transverse to the axis of the collector then the guides must be movably supported in a bearing and locked therein to prevent displacement.

It is therefore an object of the present invention to provide an improved thread guide of simple construction which may be removably mounted on a traverse member and locked for movement therewith only while the guide is in operative position.

Another object of this invention is the provision of a novel guide, the shank portion of which is received in a bearing located on a traverse member and retained in position solely by means of a projection on the shank portion which contacts a part of the traverse member to prevent withdrawal from the bearing; and hence obviating the necessity for the usual locking mechanisms.

Other objects and advantages will be apparent when considered in conjunction with the accompanying drawing wherein:

Figure 1 is a view in partial section of a guide locked to a traverse member in accordance with one form of this invention the positions thereof with respect to a collector being illustrated;

Figure 2 shows in elevation the guide of Figure 1 in its locked position;

Figure 3 shows in elevation the guide of Figure 1 in unlocked position, i. e., rotated 90° in order to remove the same from its bearing, and

Figure 4 illustrates a modified form of the invention showing the projection on the guide riding in a slot in the traverse member.

Referring to the drawing, and particularly to Figures 1 to 3 thereof, the thread guide indicated generally at 10 is formed with a U-shaped thread guiding end 11 adapted to contact a rotating bobbin 12 and to be reciprocated across the surface thereof to lay up thread 13 as it is collected in package form. The thread guide 10 is provided with a shank portion 14 extending at a

right angle to the body portion of the guide and is received in, and supported by, a bearing 15. The bearing 15 is supported in turn by an L-shaped traverse member consisting of a vertical side 16 and a horizontal reinforcing side 17. This member is mounted for reciprocation axially of the bobbin by any suitable means not shown.

The bearing 15 is screw-threaded on one end and affixed to the traverse member by means of a nut 18. In one form of the invention, the other end of the bearing 15 is provided with a shoulder 19 which is urged against the vertical side 16 of the traverse member by tightening the nut 18, and thereby rigidly supports the bearing 15. The top part of the shoulder 19 is molded in the form of a U-shaped member having a flange 20. This flange is adapted to engage a projection 21 provided on the shank portion 14 of the thread guide 10 when the said guide is in operative position. As long as the flange engages the projection, the thread guide cannot be withdrawn, although shank 14 is free to pivot in bearing 15.

In the modification shown in Figure 4, the bearing 22 acts only to support the thread guide 10. In this form the shoulder 23 also holds the bearing in a rigid position on tightening the nut 18. The traverse member consists of a vertical side 24 similar in shape and function to side 16, and a horizontal side 25 which reinforces the traverse member and also acts to lock the projection 21 and prevent displacement of the guide 10. For this purpose a slot 26 is provided in the horizontal side 25 and when the guide 10 is in operative position the projection 21 rides in the said slot.

It will be readily seen that in order to mount the guide, it can be turned to a horizontal position and the shank portion inserted in the bearing (see Figure 3). On turning the guide 90° in a direction to cause the projection to engage the flange or slot on the traverse member, the guide will be locked against withdrawal from the bearing. Accordingly, the guide will move with the traverse member, i. e., in an axial direction of the bobbin. However, as in the present case, where a so-called "suspended following guide" is employed in which the traverse member overlies the bobbin and the suspended guide contacts the package throughout the winding period, it is freely movable in an arcuate path transversely of the axis of the bobbin. It is also contemplated to use the present invention for "following guides" mounted on traverse members reciprocating axially below the collecting device. In this instance also, the guide is freely movable in a direction transverse to the axis of the collecting device.

In cases where the guide is to be used on traverse members and held in spaced relation with

respect to the collecting device throughout the winding period, then obstructions can be appropriately positioned on the traverse member to prevent any substantial movement of the guide.

This invention is not to be limited to any specific application as it is well within the purview hereof to utilize the herein-described simplified thread guide mounting in many types of traverse mechanisms; and the form of the thread guide per se is not material. It is intended to cover the broad conception of removably attaching a thread guide to a support by providing a means on the guide for engagement with another means on the support to thereby temporarily lock the same when the guide is moved into operative position. Therefore the scope of the invention is to be limited only to the extent of the appended claims.

What is claimed is:

1. In an apparatus for winding threads and the like comprising a collecting device, a traverse member reciprocating lengthwise thereof and a rigid, integral thread guide removably attached to said traverse member adapted to reciprocate therewith, the improvement which comprises means constituting part of the thread guide and coacting means on the traverse member to automatically lock the thread guide thereto, and effect longitudinal movement therewith, only when said guide is in operative position.

2. In an apparatus for winding threads and the like comprising a collecting device, a traverse member reciprocating lengthwise thereof and a rigid, integral thread guide removably attached to said traverse member adapted to reciprocate therewith, the improvement which comprises a projection on the thread guide remote from the thread contacting end and means on the traverse member adapted to engage the projection only when said guide is in operative position.

3. In an apparatus for winding threads and the like comprising a collecting device, a traverse member reciprocating lengthwise thereof and a rigid, integral thread guide removably attached to said traverse member adapted to reciprocate therewith, the improvement which comprises a projection on the thread guide remote from the thread contacting end, and a flange on the traverse member adapted to engage the projection only when the thread guide is in operative position to thereby lock the same for longitudinal movement with the traverse member.

4. In an apparatus for winding threads and the like comprising a collecting device, a traverse member reciprocating lengthwise thereof and a rigid, integral thread guide removably attached to said traverse member adapted to reciprocate therewith, the improvement which comprises a projection on the thread guide remote from the thread contacting end adapted to ride in a slot in the traverse member only when said guide is in operative position.

5. In an apparatus for winding threads and the like comprising a collecting device, a traverse member reciprocating lengthwise thereof and a rigid, integral thread guide removably attached to said traverse member adapted to reciprocate therewith, the improvement which comprises means constituting part of the thread guide coacting with a flange on the traverse member to automatically lock the thread guide thereto, and effect longitudinal movement therewith, only when said guide is in operative position.

6. In an apparatus for winding threads and the like comprising a driven bobbin and a traverse member reciprocating lengthwise thereof, a rigid, integral thread guide carried by said traverse member and removably attached thereto to reciprocate with the traverse member when in operating position, said guide being freely movable in an arc in a direction transverse to the axis of the bobbin to traverse the thread while the guide is in contact with the package as it is formed, and means for locking the guide to the traverse member only when the guide is in operative position.

7. In an apparatus for winding threads and the like comprising a driven bobbin and a traverse member overlying the same and reciprocating lengthwise thereof, a thread guide pivotally suspended from said member to reciprocate with the same when in operating position and freely movable longitudinally thereof adapted to contact the bobbin during the winding operation and means on the guide and traverse member coacting to lock the guide to effect unitary movement lengthwise of the bobbin only when said guide is in operative position.

8. In an apparatus for winding threads and the like wherein a longitudinally reciprocating traverse member carrying a thread guide is employed, the improvement which comprises a bearing in the traverse member for receiving a shank portion of the guide, a projection constituting part of the shank portion and means on the traverse member to engage the projection when the guide is in operative position to thereby prevent displacement of the guide with respect to the traverse member.

9. In apparatus for winding thread or the like including a rotating bobbin, a traverse member movable lengthwise thereof and a thread guide mounted on said traverse member for rotation about an axis substantially parallel to that of the bobbin, a projection on said thread guide extending radially of its axis of rotation, traverse member supported means defining a socket adapted to receive said projection to hold said thread guide against displacement in the direction of its axis, said socket extending for less than 360° about the axis of said guide whereby the latter may be quickly detached from the traverse member by rotation to a position in which the projection is out of registry with the socket and free axial movement is possible.

10. In apparatus for winding thread or the like including a rotating bobbin, a traverse member movable lengthwise thereof and a thread guide mounted on said traverse member for rotation about an axis substantially parallel to that of the bobbin, means defining a socket, means defining a complementary projection, one of said means being supported by said traverse member in a position radial of the axis of said thread guide and the other being supported by the thread guide radially of its axis, said means being of a size and position to lie in axial registry through a sector of a magnitude corresponding at least to the normal angular displacement of the guide in use, whereby in normal position of the guide it is locked against axial displacement by said registering means while the guide may be detached from the traverse member by angular movement beyond its normal position to relatively move said means out of registry.
